UNITED STATES PATENT OFFICE

GUIDO J. ALBRECHT AND SIDNEY L. LONG, OF MINNEAPOLIS, MINNESOTA, ASSIGNEES
TO LONG MAILING MACHINE COMPANY, OF MINNEAPOLIS, MINNESOTA, A CORPORATION.

ENVELOP-SEALING MACHINE.

1,144,955.

Specification of Letters Patent. Patented June 29, 1915.

Application filed April 20, 1911. Serial No. 622,254.

To all whom it may concern:

Be it known that we, GUIDO J. ALBRECHT and SIDNEY L. LONG, citizens of the United States, residing at Minneapolis, in the county of Hennepin and State of Minnesota, have invented certain new and useful Improvements in Envelop-Sealing Machines; and we do hereby declare the following to be a full, clear, and exact description of the invention, such as will enable others skilled in the art to which it appertains to make and use the same.

Our invention has for its object to provide a thoroughly reliable envelop sealing machine of very high capacity, and to such ends, generally stated, the invention consists of the novel devices and combinations of devices hereinafter described and defined in the claims.

20 In the attainment of the objects above briefly stated, numerous difficulties are encountered. The various kinds and character of post-office matter ranging from flimsy envelops with flimsy and light contents to envelops in which more or less bulky and irregular merchandise is inclosed, make the proper successive selection of envelops from a stack thereof contained in a supply magazine or holder, one at a time, a matter hard 25 to accomplish with certainty. Even after this proper selection has been made, there is much difficulty in properly handling and sealing these variously loaded envelops.

30 The mucilage on the envelop flaps must first be properly moistened and thereafter properly pressed closed, but the closing of the moistened envelops must not be accomplished immediately after moistening, for a sufficient time must be allowed to permit 35 the mucilage to be properly softened by the applied water. Then, and finally, the sealed envelops should be properly stacked.

40 In designing the improved machine hereinafter described, all of the above noted facts have been taken into consideration and the machine, which has been put into 45 actual use, meets all of the requirements and overcomes all of the difficult obstacles encountered in rapidly and efficiently sealing 50 all kinds of envelops with their various different kinds of loads or contents.

55 The following is a brief forecast, or general statement of the construction and action of the improved sealing machine, and which it is thought will facilitate a quick under-

standing of the more detailed description which will follow:

The loaded or filled envelops are piled in a stack with their flaps opened up in, or approximately in a plane with the bodies 60 of the envelops and are placed in a suitable supply magazine, so-called. This supply magazine has an escapement device of novel construction which will raise to permit the lowermost envelop, only, to be fed from the 65 stack, regardless of the thickness of the said envelop, or the character of its contents.

70 From the magazine, the envelops are fed from the bottom of the stack, one at a time, by a novel feed device comprising a reciprocating head having one or more long and preferably flat spring fingers, the free ends of which move in the plane of the open mouth of the lowermost envelop and are arranged to enter the envelop and to feed the 75 same from the bottom of the stack by pressure against the back or bottom edge of the envelop. By means of this feed device and coöperating rollers the ejected envelop with its flap still open is fed to and past a moistening device which applies the moisture properly to the gummed surface of the open envelop flap.

80 From the moistening device, the envelops are fed to a transfer device in the form of 85 an intermediate rotating reel. By the rotation of this reel and the coöperating action of a segmental sheath, the moistened flaps of the envelops are partly closed, or turned 90 back so that they may be easily, thereafter, closed, by the action of the sealing rollers, to which latter they are delivered by the said reel. The reel performs an additional and highly important service, to-wit, it carries 95 and holds the envelops for a sufficient length of time to permit the moistened gum on the flaps of the envelops to become soft and sticky, so that when the flap is closed the mucilage, or gum, will have its full adhesive action.

100 The envelops are delivered to the sealing rollers, as stated, with their flaps turned backward, and certain of these said sealing rollers are preferably made sectional with sections independently spring pressed so 105 that they will adapt themselves to irregularities in the contents of the envelops.

110 The sealed envelops pass from the sealing rollers to a stacking device by which they are tightly pressed together and held in

compact form while the drying of the sealed envelops is completed and until the envelops are removed from the delivery end of the stack.

- 5 The present invention is particularly directed to the provision of an improved envelop moistening and transferring mechanism, and to the novel coöperative arrangement of the same.
- 10 In the accompanying drawings which illustrate the improved machine, like characters indicate like parts throughout the several views.
- Referring to the drawings, Figure 1 is 15 a left side elevation of the complete machine; Fig. 2 is a plan view of the improved machine with the envelop magazine removed; Fig. 3 is a vertical section taken from front to rear through the complete 20 machine, approximately on the line $x^3 x^3$ of Fig. 2; Fig. 4 is an enlarged vertical section showing the upper portion of the machine, including chiefly the envelop magazine, the envelop feed device, and the moistening device, the said section being taken 25 approximately on the line $x^4 x^4$ of Fig. 2; Fig. 5 is a view in left side elevation showing, on a larger scale than the other views, the mechanism of the upper portion of the machine; Fig. 6 is a perspective view with some parts broken away, illustrating the action of the spring fingers of the envelop feed head; Fig. 7 is a vertical section taken on the line $x^7 x^7$ of Fig. 2; Fig. 8 is a plan 30 view of the envelop magazine, some parts being broken away; Fig. 9 is a vertical section taken on the line $x^8 x^9$ of Fig. 8; Fig. 10 is a horizontal section taken on the line $x^{10} x^{10}$ of Fig. 3 showing the sealing rollers; Fig. 11 is a vertical section taken on the line $x^{11} x^{11}$ of Fig. 10, some parts being broken away; Fig. 12 is a fragmentary view in vertical section on the line $x^{12} x^{12}$ of Fig. 10; Fig. 13 is a rear elevation showing the main 45 feed roller and connected devices, some parts being broken away; Fig. 14 is a transverse section taken on the line $x^{14} x^{14}$ of Fig. 13, some parts being broken away and some parts being removed, and showing also a 50 roller which coöperates with the said main feed roller; Fig. 15 is a section taken on the line $x^{15} x^{15}$ of Fig. 13, some parts being broken away and some parts being removed, and showing also a roller which coöperates 55 with the said main feed roller; Fig. 16 is a detail in section on the line $x^{16} x^{16}$ of Fig. 13; Fig. 17 is an enlarged view corresponding in the line of its section to Fig. 3 and illustrating the envelop packer; Fig. 18 is a 60 left side elevation showing the mechanism for operating the envelop packer; Fig. 19 is a plan view showing the supporting table of the envelop packer and a tension device in the movable resistance plate or member thereof; and Fig. 20 which is shown on the

same sheet as Fig. 6, is a transverse vertical section taken on the line $x^{20} x^{20}$ of Fig. 17.

The framework 1 of the machine is shown as made up chiefly of a pair of laterally spaced plates or brackets tied together by suitable cross connections, including, as shown, a bottom shelf 2, which latter, in the present instance, is utilized to support a small electric motor 3 for driving the machine. The motor shaft carries a pulley 4, and a driving belt 5 runs over this pulley and over a much larger pulley 6, carried by a transverse shaft 7 journaled in the intermediate upper portion of the frame brackets 1. 75

Envelop magazine.—The envelops a with the gummed flaps a^1 turned open, as above stated, and as best shown in Fig. 4, are arranged in a stack and are placed upon the bottom of the envelop magazine. The bottom or feed table member of this envelop magazine is preferably inclined and of skeleton form, being indicated as an entirety by the numeral 8, and having its sides rigidly secured to the upper portions of the frame brackets 1. The back of the magazine, against which the bottom edges of the envelops are engaged, is also preferably slightly inclined and, as shown, it is afforded by laterally projecting flanges of channel plates 9 that are rigidly secured to a fixed transverse tie bar 1^a of the main frame. The lower ends of the bars 9 terminate sufficiently above the feed table 8 to permit the largest and most heavily loaded envelop to be fed thereunder. The side plates 10 of the magazine are laterally spaced and are adjustable toward and from each other, preferably by means which keep the same always equidistant from the transverse center of the machine. As shown, the said adjustable side plates 10 are provided with hubs 11 (see particularly Figs. 8 and 9) arranged to slide on the tie bar 1^a of the machine frame. To the central portion of the tie bar 1^a there is, as shown, rigidly secured a bearing 12, to which the intermediate joint of a lazy tong 13 is pivotally attached. The outer joints of the lazy tong 13 are shown as pivoted to metal arms 14 rigidly secured to the hubs 11 of the adjustable side plates 10. This lazy tong connection between the side plates 10, as is evident, keeps the said side plates always equidistant from the transverse center of the machine under the various adjustments of the said side plates required for envelops of different lengths. This is important because it keeps envelops, regardless of length, with their central portions always at the same place in respect to the various parts of the machine. 100

The envelop magazine is provided with an escapement device of novel construction which holds back the lowermost envelop and permits the escape or discharge of only 105

one envelop at a time. This escapement device is best shown in Figs. 4, 8 and 9, and it comprises a stop blade 15 that is secured to and depends from a pair of laterally spaced upright bars 16 that are connected by parallel links 17 to the fixed bars 9. The parallel links 17, it will be noted, are oblique in respect to the plane of the feed table 8 so that when the stop blade 15 is pressed rearward the said parallel links will cause the said blade to rise and pass over the envelop pressed against the said blade, but immediately, when the said blade is passed to the upper surface of the lowermost outpassing envelop, it will be raised no further and will hold back the envelop second from the bottom. Preferably, light leaf springs 18, attached to the upper ends of the bars 9 engage the upper ends of the movable bars 16, and hence, assist gravity in yieldingly pressing the stop blade 15 downward. The tension of the springs 18 is adapted to be varied by set screws 19 that work through projections of the bars 9.

25 *Envelop feed mechanism.*—A feed head 20 in the form of a plate is arranged to slide toward and from the escapement stop blade 15 in runways 21 shown as formed in intermediate bars of the feed table 8. This feed head 20 carries several, as shown three, long and flat spring feeding fingers 22 attached thereto at one end, and with their free ends projecting slightly upward and in front of the feed head in position to enter the bottom envelop of the stack and to engage the back edge thereof to force the said envelop against and under the escapement stop blade 15. These spring fingers should be very flexible, and hence, they are attached to the feed head 20 only at one end, so that their free ends will adapt themselves to different envelopes regardless of the thickness of their load or fillers. In some instances, it is thought to be desirable to provide small spring-pressed levers 23, shown in Fig. 4, having at their free ends, laterally projecting pins 24 pressing upward on the free ends of the spring fingers 22 when the latter are retracted or moved into their most forward position shown in Fig. 4. These levers 23 are shown as pivoted to brackets 25 secured to the upper front portion of the machine frame. The levers 23 act on the spring fingers 22 while they are entering the lower envelop, but immediately thereafter, the front edge of the feed head 20 strikes the said levers and forces the same downward into inoperative position. To hold up the open flaps 1^a of the envelop so that the free ends of the fingers 22 will freely pass under the lower one, a stiff flap supporting finger 26 is secured to the upper front end of the feed table 8 with its free end underlying and supporting the said lowermost flap. In Fig. 4, the envelop flap is not shown as engaged

with the said finger 26, but when a stack of envelopes is placed in the magazine, the said lower flap will be pressed downward against the ends of the said finger. It is important to note that when the feed head 20 is retracted or moved forward and upward, to its normal limit, the free ends of the fingers 22 move beyond the body of envelopes but are not withdrawn from under the flap of the last envelop. Hence, the said fingers cannot by any possibility, be forced off the top of the bottom envelop and are spring pressed upward so that when moved in the direction to feed the envelop, it will run along the undersurface of the top sheet of the envelop and, hence, will not engage with the contents of the envelop.

The feed head 20 is given sufficient movement to cause the fingers 22 to feed the bottom envelop nearly or quite out of the magazine and into engagement with feed rollers, hereinafter described, by which the said envelop is subjected to and moved passed the moistening device. To thus reciprocate the feed head 20, it is shown as connected by a link 27 to the upper end of an arm 28, the lower end of which is secured to a rock shaft 29, journaled in the frame brackets 1. To the outer end of the rock shaft 29 is secured another arm 30. The free end of the arm 30 is connected by a link 31 to an adjustable throw crank 32 (see particularly Figs. 1 and 5). This adjustable throw 32 is carried by an under gear 33 journaled to the left hand frame bracket 1. The adjustable throw crank 32 is shown as connected to the gear 33 by an axial stud 34 and coöperating lock screw 35, both of which work in a longitudinal slot of the said crank. Preferably, the crank is marked or graduated to indicate when the same is properly set for the feeding of the envelopes of different widths (see particularly Fig. 5). In Fig. 4 there is shown light depending spring rods 36 secured at their upper ends to the frame tie bar 1^a with their free ends in position to slightly press downward on the envelopes as they are fed from the magazine. By radial adjustments of the crank 32, the envelop feeding fingers 22 are set for proper feed movements for envelopes of different widths.

Moistening device and coöperating feed rollers.—The moistening device illustrated comprises a pair of frictionally engaging rollers 37 and 38, the former of which has a shaft 39 extended through and journaled in the frame brackets 1, and the latter of which is journaled in the water box or tank 40 with its lower portion arranged to work in the water z contained therein. Both of the rollers 37 and 38 are preferably faced with absorbent material such as cloth. The tank 40 is shown as secured to the upper ends of a pair of plates 41 that are pivoted

at 41^a to the frame brackets 1 and are mounted for pivotal adjustments so that the roller 38 may be set under varying pressure for engagement with the roller 37, or may be moved entirely out of engagement with the same whenever it is desired to remove the roller 38 or to throw the moistening device out of action. Preferably, the adjustment of the plates 41 is accomplished by thumb screws 42 that are screwed into the frame bracket 1 and work in slots 43 of said plates, as shown in Fig. 4. The lower shaft 39 at one end (see Fig. 5) is provided with a ratchet wheel 44 in which co-operates a spring pressed retaining pawl 45 mounted, as shown, on the lefthand frame bracket 1. To intermittently rotate the water distributing or applying roller 37, the ratchet wheel 44 is acted upon by a spring pressed driving pawl 46 that is eccentrically pivoted at 47 to a spur gear 48 journaled on the left-hand frame bracket 1 and in mesh with the spur gear 38, before noted.

The envelops when fed from the bottom 25 of the magazine, are directed toward the upper surface of the moistening roller 37 with the gummed surface of their flap downward for contact with the wet surfaces of the said roller. On their way to the said 30 roller 37, they are passed over a continuously driven roller 49, the shaft of which is journaled in the frame brackets 1 and projects through one thereof, and is provided at its righthand end with a sprocket 50 indicated by dotted lines in Fig. 7. For co- 35 operation with the roller 49, there is a movable idle roller 51 journaled in the upper ends of a pair of levers 52 that are pivoted at their lower ends to the frame brackets 1 40 and are provided with laterally projecting rollers 53 that work on cams 54 (see particularly Figs. 4, 7, 13 and 16). These cams are carried by a continuously running motor driven shaft 7, already noted. Levers 45 52 are yieldingly drawn downward by coiled springs 55 that tend to engage the roller 51 with the roller 49.

From the moistening roller 37 the envelops are delivered to the upper surface of a 50 large segmental main feed roller 56 which is carried by the driving shaft 7. For co-operation with this segmental feed roller 56, there is provided an idle presser roller 57 journaled to the free ends of a pair of levers 58 pivoted at their lower ends to the frame brackets 1. To properly control the movements of the presser roller 57 toward and from the feed roller 56, a pair of cams 59 are carried by the shaft 7 and operate on the 60 end portions of the said presser roller 57. Coiled springs 60 are connected between the levers 58 and frame brackets 1 and tend to move the roller 57 into engagement with the roller 56.

05 The segmental surface of the main feed

roller 56 is of sufficient extent to afford the proper support for the envelops and to impart thereto the proper feed movements, but its cut-away portion clears the gummed parts of the envelop flap. As shown, the 70 said segmental roller 56 is provided with a supplemental section 56^a which engages with the ungummed portion of the envelop flap.

A flap presser 61 for pressing the gummed portion of the flaps against the wet surface 75 of the moistening roller 37, is secured to the upper ends of a pair of levers 62 that are pivoted at 63 to the frame brackets 1. Coiled springs 64 (see Fig. 4) tend to engage the comb 61 with the moistening roller 80 37. Each lever 62 is provided with a laterally projecting roller 65 that works on a cam 66 carried by the motor driven shaft 7. These cams 66 affect the movements of the comb 61 toward and from the rollers 37 at 85 the proper times.

The cams 54 are so constructed and timed that they hold the presser roller 61 raised, as shown in Fig. 4, while the envelop is being passed between the same, and the roller 90 49, and immediately thereafter, they permit the said roller 61 to lower and thereby press the envelop against the roller 49 so that the envelop will be fed onward over the moistening roller 37. The cams 66 are so constructed and timed that the presser 61 will be raised at the proper time to permit the body of the envelop to pass under the same and over the moistening roller 37, but they will cause the said comb to descend to the 95 outer surface of the gummed flap and press the gummed flap against the said moistening roller. The cams 59 are so constructed and timed that they will hold the presser roller 57 raised or retracted from the segmental main feed roller 56 until the bottom edge of the envelop has been delivered between the same and the said segmental roller, and as soon as the envelop reaches this position, the said cams will permit the 100 110 said presser roller 57 to descend on to the same thereby pressing the envelop against the said main feed roller and insuring the proper feed movement thereof under the rotation of the said main feed roller 56. By 115 the means described, the gummed flap of the envelops will be properly moistened.

The above described feed rollers which control the movements of the envelops to and past the moistening device or roller, also 120 serve to deliver the envelops to the so-called transfer reel.

The cams 54 which operate the roller 51 are so timed that the said roller 51 will be moved against the cooperating roller 49 immediately after an envelop has been started between the same by the feed fingers 22.

The pawl and ratchet device which operates the moistening roller 37 is so timed that the said roller will remain stationary at a 13

time when the member 61 presses the gummed flap of the envelop against the moist surface of the roller.

Transfer reel and associating devices.—
5 The transfer reel, as preferably constructed, is in the form of a transverse shaft 67 having a multiplicity of laterally spaced pairs of radial prongs 68 arranged to afford radial compartments into which the envelops 10 are adapted to be inserted edgewise with their bottom edges directed inward and with their moistened flaps projecting outward from the receiving compartments afforded by the said pairs of prongs. As illustrated, 15 the reel is thus formed with six envelop receiving compartments, and hence, the reel shaft 67, which is journaled on the frame brackets 1, is provided at one projecting end with a six-toothed ratchet wheel 69 shown 20 in Figs. 1, 2 and 5.

The reel is given an intermittent six-step rotation by a spring pressed driving dog 70 which, as shown, acts upon the ratchet wheel 69, works through a keeper guide 71 on the 25 adjacent frame bracket and, like the driving pawl 46, is eccentrically pivoted at 47 to the continuously driven gear 48.

Extending quite close to the outer ends of 30 the reel prongs 68 and also intermediate thereof, from a point nearly vertically below the shaft 67, preferably to a point above the presser roller 57, is a segmental sheath 35 shown as made up of three thin metal strips 72. As shown, these strips 72 are supported from the frame bracket 1 by small transverse rods 73 and 74.

The reel is rotated in the direction of the arrows marked adjacent thereto on Figs. 3 and 11, and under rotation of the reel, in this 40 direction, the moistened gummed flaps will be engaged with the segmental strips 72 and turned backward or toward closed positions approximately as indicated in Figs. 3 and 11.

From the downturned compartment of the 45 reel, the inverted envelop is delivered to the sealing rollers and to insure the downward discharge of the envelop from the reel, an automatic ejector is employed. This ejector (see Figs. 3, 4, and 7) is in the form of a long arm 75 secured to a transverse shaft 76 that is pivoted in the frame brackets 1. At 50 its free end, this ejector arm 75 is provided with a head 77 that normally stands in position to engage the upturned edge of the inverted, downturned envelop so that when the said lever is released it will fall by gravity, or, if desired, by the assistance of a spring, not shown, and will, as indicated, insure the 55 discharge of the said envelop and the proper delivery thereof to the sealing rollers. The properly timed movements of the ejector arms 75 are controlled by a cam 78 that operates on a roller or lateral projection 79 of 60 the said arm. This cam 78 is carried by a transverse shaft 80 journaled in the frame 65

brackets 1 and provided at one end with an under gear 81 that meshes with the continuously driven gear 33, before described, (see Fig. 5).

A retaining disk 82 (see Fig. 7) is secured 70 to the reel shaft 67. This disk 82 is provided with six V-shaped notches 83 that are engaged by the V-shaped point of a spring pressed retaining dog 84 pivoted to one of the frame brackets 1. The disk 83 and co-operating dog 84 yieldingly hold the reel in 75 its several different positions and prevent accidental movements thereof, and furthermore, insure proper alignment with the downturned compartment of the wheel with 80 the sealing rollers and of the reel compartment which is in a receiving position with the contacting surfaces of the rollers 56 and 57. The numeral 85 indicates a yielding stop plate suitably supported from the 85 frame brackets 1 in position to assist in directing the downturned and discharged envelop from the reel to the sealing rollers.

The stop plate 85 is shown as pivoted on a transverse rod 85^a and is subject to a torsional spring 85^b. This spring 85^b normally holds said plate 85, as shown in Figs. 3, 11 and 20, but permits the same to yield, and thereby prevents clogging of the machine in case an envelop should become crowded and 95 caught at the point of delivery to the sealing rollers.

Sealing rollers.—To seal the envelops, they are preferably run between the pairs of sealing rollers, which pairs are located 100 one over the other, as best shown in Figs. 3, 7, 10 and 11. Both of these pairs of rollers are alike and one member of each pair is a continuous smooth roller 86, while the co-operating so-called roller of each pair is 105 made up of a multiplicity of roller sections or wheels 87 journaled in plungers 88, mounted for movements toward and from the co-operating rollers 86 and suitable bearing bars 89 and 90. The bars 89 are rigidly 110 supported by the pedestal side frames 1, while the bar 90 is movable and is made adjustable by set screws 91 that work through suitable bearings 92 secured on the frame brackets 1. Coiled springs 93 are placed on 115 the plungers 88 and are compressed between the adjustable plate 90 and pins 94 carried by the said plungers. The function of the springs 93 is to permit an independent yielding movement of the plungers 88 and the 120 roller sections carried thereby, so that when an envelop carrying an object of irregular form is passed between the co-operating sealing rollers, all portions of the gummed envelop flap will, nevertheless, be tightly 125 pressed and the envelop thoroughly sealed. By reference to Fig. 10, it will be noted, that the roller section or wheels 87 of the upper and lower sectional presser rollers are staggered and overlapped so that the gummed 130

flap of the envelop passing between the same will be pressed at all points.

The upper sealing roller 86 is provided at one end (see Figs. 7 and 10) with a small sprocket 95 that is driven by an endless sprocket chain 96. This sprocket chain 96 which is indicated by dotted lines in Fig. 7 and full lines in Figs. 2 and 3, runs over and is driven by a larger sprocket 97 (see Figs. 10, 2, 7 and 13) which is carried by the driving shaft 7. This sprocket chain 96 also runs over the sprocket 50 of the feed roller 49 and, hence, continuously drives the latter. The said sprocket chain 96 is also guided by idlers 98 and 99 mounted on one of the frame brackets 1, as shown in Fig. 7.

To drive the lower sealing roller 86 from the upper to the shafts of said rollers which are journaled in the frame brackets 1, they are provided with under gears 100 that mesh 20 with an intermediate under gear 101 journaled to the adjacent frame bracket 1, as best shown in Figs. 10 and 12.

Envelop packer.—From the sealing rollers the sealed envelops are fed edgewise downward to the so-called packer where they are accumulated in an approximately horizontal stack and closely packed together while the drying of the gummed flaps is completed. The so-called packer includes a long table or deck 102 provided with laterally spaced guide rails 103, all but the front portions of which are loose and the rear ends thereof being yieldingly drawn toward each other by a coiled spring 104. For this packer mechanism, attention is particularly called to Figs. 1, 3 and 17 to 20 inclusive. Mounted to slide on the table 102 between the rails 103 and frictionally held thereby is 30 an envelop receiving rack in the form of a flat plate 105 having an upturned rear end 106. The envelops are delivered directly on to this plate 105 and the first envelop is packed against the rear end 106 thereof. 40 The envelops are delivered just at the rear of a packer plate or head 107 which is carried by the free end of a long link 108, which at the front end of the machine is pivoted to an arm 109 of a rock shaft 110, which latter is journaled in the front portions of the frame brackets 1. At one end, to-wit, as shown at its left hand end, the rock shaft 110 is provided with another arm 111 that is connected by a link 112, to a crank pin 50 113 carried by a continuously driven gear 81 already described.

When the gear 81 is rotated, the packer head 107 will, as is evident, be reciprocated toward and from the upturned end 106 of 60 the movable plate 105.

The last envelop *a* packed upon the plate 105 is engaged and the stack of envelops held in position by retaining fingers 114 that are carried by a rock shaft 115 mounted in 65 the rear legs of the frame bracket 1. By

reference to Fig. 17, it will be seen that when a sealed envelop is first dropped back of the packer head 107, it will stand in front of the transverse portion of the retaining fingers 114. At a time just before the 70 packer head is moved against the last deposited envelop, the fingers 114 will be raised into their uppermost in-operative position shown by the dotted lines in Fig. 17, by the action of the operating mechanism, 75 as best shown in Figs. 1, 17 and 18. It may be here also noted that the rock shaft 115 carries a centrally located finger 116 that normally keeps the envelops pressed downward upon the movable plate 105. 80

At one end, to-wit, as shown, its left hand end, the rock shaft 115 is provided with a flat plate-like arm 117 that is subject to a coiled tension spring 118 that is anchored to the adjacent frame bracket 1 (see particularly Fig. 18). On the arm 117 is a projecting stud 119 that cooperates with a triangular cam head 120 that is pivoted at 121 to the rear end of a long bar 122. This bar 122 is mounted to slide endwise through a keeper 123 on the left hand frame bracket 1, and at its front end, it is pivotally attached to the lower end of the arm 111 of the rock shaft 110. The full lines in Fig. 18 indicate the position of the parts therein shown 95 when the packer head 107 is in the position shown by full lines in Figs. 3 and 17. The cam head 120 is provided with a weighted arm 124 which normally holds the same against the stud 119 as shown in Fig. 18. 100 When the packer head 107 and the bar 122 moves forward or toward the right in respect to Figs. 17 and 18, the cam head 120 will first be carried forward of the stud 119 and it will then, by gravity, be dropped into the position indicated by light dotted lines in Fig. 18, its movement in this direction being limited by a stop pin 125 on the said bar 122. Then when the said packer head 107 and bar 122 are moved rearward or 105 toward the left in respect to Fig. 17 and Fig. 18, the inclined surface of the cam head 120 will engage the stud 119 and force the lever 117 into the position indicated by heavy dotted lines in Fig. 18. A little farther rearward movement of said cam head will carry the same under the stud 119 and the spring 118 will then throw the lever 117 back to its normal or full line position, Fig. 18. When the lever 117 is in the position shown by heavy dotted lines in Fig. 18, the so-called retaining fingers 114 will be raised above the envelops on the plate 105 and the said fingers will be dropped into engagements with the last packed envelop before 115 the packer head recedes therefrom. When the packer head 107 and bar 122 are moved forward or toward the right in respect to Figs. 17 and 18, the stud 119 will engage the upper edge of the cam head 120 and force 120 125 130

the same back into its normal position shown by full lines in Fig. 18.

What I claim is:

1. A machine for sealing envelopes comprising two pairs of forwarding rollers and an intermediate moistening device, initial feeding means to present the envelopes singly and successively to the first pair of rollers, and means timed with respect to the action of said initial feeding means to press the flap of the envelop against said moistening device after both sets of rollers have operated to forward the body of said envelop past said moistening device.
15. 2. A machine for operating upon envelopes comprising two pairs of rollers operative to forward an envelop in a single plane and an intermediate moistening device having its operative surface out of said plane, initial feeding means to present the envelop singly and successively to the first pair of rollers, a bar and means timed with respect to the action of said initial feeding means to move the bar to cause the same to press the flap against said moistening surface after both sets of rollers have operated to forward the body of the envelop past said moistening device.
30. 3. A machine for operating upon envelopes comprising two pairs of rollers operative to forward an envelop in a single plane and an intermediate moistening device having its operative surface out of said plane, initial feeding means to present the envelopes singly and successively to the first pair of rollers, a presser bar, and means timed with respect to the action of said initial feeding means to move the bar edgewise to cause the same to press the flap against said moistening surface after both sets of rollers have operated to forward the body of the envelop past said moistening device.
35. 4. The combination with a moistening device, of means for feeding the envelopes to and past said moistening device comprising a pair of rollers in front and a pair of rollers at the rear of said moistening device, means operative intermittently to present envelopes singly and successively to the first pair of rollers, and an intermittently operative flap pressing device timed with respect to the action of said presenting means to press the gummed flaps against said moistening device after the front pair of rollers has delivered the envelopes and while the envelop is subjected to the action of the rear pair of rollers.
45. 5. The combination with a moistening device and means for causing the same to operate intermittently, of means for feeding the envelopes to and past said moistening device comprising a pair of rollers in front and a pair of rollers at the rear of said moistening device, and means to present the envelopes singly and successively to the front

pair of rollers, and means for intermittently separating and closing the members of the said pairs of rollers timed with respect to the actions of said feeding means and moistening device so that the envelopes will be forwarded and moistened in definitely timed succession.

6. The combination with a moistening device, of means for feeding the envelopes to and past said moistening device comprising a pair of rollers in front and a pair of rollers at the rear of said moistening device and means to present the envelopes singly and successively to the front pair of rollers, and means operative intermittently to separate and close the members of said pairs of rollers timed with respect to the actions of said feeding means so that the envelopes will be moved past said moistening device in definitely timed succession.

7. The combination with an envelop magazine and a reciprocating envelop feeding device, of a moistening device and a pair of rollers on each side thereof, at least one member of each pair being constantly driven, and means for separating and closing the first pair of rollers timed in action so that the rollers will be separated when the reciprocating device presents an envelop between the same and thereafter will be closed to forward the envelopes past the moistening device in definitely timed succession.

8. The combination with an envelop magazine and a reciprocating envelop feeding device, of a pair of intermittently separated rollers receiving the envelopes direct from said magazine, a second pair of rollers receiving the envelopes from the first pair of rollers, a moistening device located between the said pairs of rollers and to which the gummed flaps of the envelopes are delivered by the said rollers, and an intermittently operative flap pressing device timed to press the gummed flaps of the envelopes against the said moistening device while the envelop bodies are subject to the said second pair of feed rollers.

9. The combination with an envelop magazine and a reciprocating envelop feeding device, of a pair of intermittently separated rollers receiving the envelopes direct from said magazine, a second pair of rollers receiving the envelopes from the first pair of rollers, a moistening device located between the said pairs of rollers and to which the gummed flaps of the envelopes are delivered by the said rollers, levers provided with a flap pressing blade co-operating with the said moistening device, and a cam operative on said lever and timed to cause the said flap pressing blade to press the gummed flap of the envelop against said moistening device, substantially as described.

- 8
10. The combination with an envelop magazine and a reciprocating feed device for discharging the envelops, one at a time, from said magazine, of a moistening device including a rotary water distributing roller, a pair of feed rollers receiving the envelops from said magazine and forwarding the bodies thereof past said moistening device, a second pair of feed rollers receiving the envelops from said moistening device, and an intermittently operative flap pressing device coöperating with the said moistening roller and timed to press the gummed flap of the envelop against said distributing roller while the body of the envelop is subject to the second pair of feed rollers.
11. The combination with a flap moistening device and means for feeding the envelops singly and in timed succession to and over the same, body portions first and extended flaps last, including a pair of co-operating feed rollers receiving the closed edges of the envelops and operative on the bodies thereof while the gummed flaps are subject to the said moistening device, and means for intermittently separating the said rollers timed to effect the separation thereof while said closed edges are being inserted between the said rollers.
12. The combination with a flap moistening device and means for feeding the envelops singly and in timed succession to and past the same, of an envelop transferring device, said feeding means including intermittently separated feed rollers for directing the envelops from said moistening device to said transferring device, and envelop sealing means receiving the envelops from said transferring device.
13. The combination with a moistening roller, of means for feeding envelops to and past said roller, and means for intermittently moving said moistening roller, timed to permit said roller to remain stationary while the gummed flap of the envelop is being fed over the same.
14. The combination with a moistening roller, of means for feeding the envelops to and past the same, means for pressing the gummed flaps of the envelops against said moistening roller, and means for intermittently moving said moistening roller, timed to permit the same to remain stationary while the gummed flap of the envelop is being pressed against and is being drawn over the same.
15. The combination with an envelop magazine and means for discharging the envelops therefrom, one at a time, of two pairs of coöperating feed rollers receiving the envelops from said magazine, a moistening device located between the said two pairs of rollers and over which the second pair draws the extended flaps, an envelop transferring device receiving the envelops from the said
- rollers, and envelop sealing rollers receiving the envelops from said transferring device.
16. The combination with an envelop magazine and a reciprocatory feed device for discharging the envelops therefrom, one at a time, of two pairs of intermittently separated feed rollers receiving the envelops from said feeder, a moistening device located between the said two pairs of rollers, a transferring device receiving the envelops from the second pair of feed rollers, an intermittently operated flap pressing device coöperating with the said moistening device, and sealing rollers receiving the envelops from said transferring device.
17. The combination with a flap moistening device and means for directing the envelops thereto, of an envelop transferring device, a pair of coöperating feed rollers each movable relatively to the moistener, one of which is segmental, for directing the envelops from said moistening device to said transferring device, and envelop sealing means receiving the envelops from said transferring device.
18. The combination with a flap moistening device and means for directing the envelops thereto, of an envelop transferring device, a pair of intermittently separated feed rollers, one of which is segmental, operative to direct the envelops from said moistening device to said transferring device, and envelop sealing means receiving the envelops from said transferring device.
19. The combination with a flap moistening device and means for directing the envelops thereto, of an intermittently operative flap pressing device coöperating with the said moistening device, an envelop transferring device adapted to carry a multiplicity of envelops, coöperating feed rollers for directing the envelops from said moistening device to said transferring device, and envelop sealing means receiving the envelops from said transferring device.
20. The combination with a flap moistening device and means for directing the envelops thereto, of an intermittently operative flap pressing device coöperating with the said moistening device, an envelop transferring device adapted to carry a multiplicity of envelops, coöperating feed rollers for directing the envelops from said moistening device to said transferring device, envelop sealing means receiving the envelops from said transferring device, and a timed ejecting device operative to insure the delivery of the envelops from said transferring device to said sealing means.
21. The combination with a flap moistening device of means for feeding the envelops singly and in timed succession to and past the same, including a pair of coöperating feed rollers forwarding the envelops from

5 said moistening device, one of the said feed rollers being made segmental, and means for intermittently separating and closing the said feed rollers, timed in action so that the rollers will be closed upon an envelop after the same is inserted between the same by the feeding means to forward the envelops by the curved portion of the segmental roller, while the moistened flaps will pass opposite and will not engage the cut-away portions thereof.

10 22. The combination with a flap moistening device and means for feeding the envelops singly and in timed succession to and past the same, of an intermittent flap pressing device coöperating with said moistening device and timed to press the gummed envelop flaps against the said moistening device, the said feeding means including a pair 15 of coöperating feed rollers forwarding the envelops from the said moistening device, one of the said rollers being segmental and timed so that the moistened gum on the flaps of the envelops will pass opposite the cut-away portion of and will not be engaged with the said rollers.

20 23. The combination with a flap moistening device and means for feeding the envelops singly and in timed succession to and past the same, including a pair of coöperating feed rollers receiving the envelops from said moistening device and operative on the bodies thereof while the gummed flaps are subject to the said moistening device, means 25 for intermittently separating and closing the said rollers timed to effect engagement thereof with the envelops after the same have been inserted between the said rollers, and one of the said feed rollers being segmental 30 and timed with respect to said closing so that the moistened gum on the flaps of the envelops will pass opposite the cut-away portion and will not be engaged by the said rollers.

35 24. The combination with an envelop magazine and a reciprocating feed device for discharging the envelops, one at a time, from said magazine, of a moistening device including a rotary water distributing roller, 40 a pair of feed rollers receiving the envelops from said magazine and delivering the same to said moistening device, a second pair of feed rollers forwarding the envelops from said moistening device, and an intermittently 45 operative flap pressing device coöperating with the said moistening roller and timed to press the gummed flap of the envelop against said distributing roller while the body of the envelop is subject to the second pair of feed 50 rollers, one of the second pair of feed rollers being made segmental so that the moistened flap of the envelop will not be engaged by the said roller.

55 25. An envelop sealing machine comprising a flap moistener and sealing means, and

means to feed the envelops singly and in timed succession with their flaps extended over the moistener and to the sealer, including a transferring member and a pair of rollers delivering the envelops thereto, one 70 of said rollers being segmental and timed in action so that the transferring member may withdraw the envelop flap from between the rollers without contact of the moistened gum thereon.

75 26. An envelop sealing machine comprising sealing rollers and an intermittently movable flap-moistening device, a transferring reel, means, including a roller operative upon one envelop at each complete revolution thereof, for forwarding the envelop in timed succession over the moistening device and to the reel, and connections from said roller for moving the moistening device and the reel one step at each revolution of the 80 roller.

85 27. An envelop sealing machine comprising sealing rollers and an intermittently movable flap-moistening device, a transferring reel, means, including a roller operative upon one envelop at each complete revolution thereof, for forwarding the envelops in timed succession over the moistening device and to the reel, said roller being constructed and arranged for engagement with an envelop during a portion of its revolution only, and connections from said roller operating during the non-engaging portion of each revolution to move the transferring device and the moistening device one step. 90

95 28. An envelop sealing machine comprising moistening means and sealing rollers, a transferring and flap closing device between said moistening means and sealing rollers comprising a multiplicity of compartments to carry moistened envelops simultaneously and present them one at a time to the sealing rollers, and means operative to pull the open flaps of the envelops over the moistening device and deliver the envelops closed-edge 100 first into successive compartments of the transferring device.

105 29. An envelop sealing machine comprising moistening means and sealing rollers, an intermediate transferring and flap closing device adapted to carry a multiplicity of moistened envelops and present them one at a time to the sealing rollers, and a pair of rollers operative to pull the open flaps of the envelops over the moistening device and deliver the envelops closed-edge first into successive compartments of the transferring device. 110

115 30. An envelop sealing machine comprising sealing rollers operative in a vertical plane, a moistening device, means for forwarding envelops with their flaps extended singly and in timed succession past said moistening device in another plane, and means for receiving the envelops in the 120 125 130

moistening plane and transferring them bodily into the sealing plane, and fixed means in the path of movement of the flaps for partially closing the same as the envelops are transferred.

31. An envelop sealing machine comprising sealing rollers operative in a vertical plane, a moistening device, means for forwarding envelops with their flaps extended singly and in timed succession past said moistening device in another plane, means for receiving the envelops in the moistening plane and transferring them bodily into the sealing plane, fixed means in the path of movement of the flaps for partially closing the same as the envelops are transferred, and means for starting the envelops from the transferring means to the sealing rollers.

32. An envelop sealing machine comprising sealing rollers operative in a vertical plane, a moistening device, means for forwarding envelops with their flaps extended singly and in timed succession past said moistening device in another plane, a transferring reel comprising a multiplicity of radial compartments one of which at all times lies in the moistening plane and one in the sealing plane, and means for moving the reel timed with said forwarding means to bring new compartments successively into each of said planes.

33. An envelop sealing machine comprising a flap-moistening device and sealing rollers, an intermittently movable transferring device operative between the moistening device in one plane and the sealing device in another plane, means, including a roller operative upon an envelop at each complete revolution thereof, for forwarding the envelop in timed succession over the moistening device and into the transferring device, and means operative once for each revolution of the roller to move the transferring device one step.

34. An envelop sealing machine comprising sealing rollers operative in a vertical plane, a moistening device, means for forwarding envelops with their flaps extended singly and in timed succession past said moistening device in another plane, a transferring reel comprising a multiplicity of radial compartments one of which at all times lies in the moistening plane and one in the sealing plane, means for moving the reel timed with said forwarding means to bring new compartments successively into each of said planes, and a semi-circular sheath extending about said reel from a point above the moistening plane to a point just short of the sealing plane and operative to partially turn the flaps and through said end adjacent the sealing plane to close and guide the flaps between the sealing rollers.

35. The combination with a flap moistening device, of a rotated envelop transferring

reel, coöperating feed rollers, one of which is segmental, for directing the envelops to the said reel with their moistened flaps open, means associated with the said reel and operative under rotation thereof to turn the moistened flaps toward closed position, sealing rollers receiving the envelops from the downturned compartment of said reel, and an intermittently operative envelop ejector for insuring delivery of the envelops from said reel to the said sealing rollers.

36. In a machine of the kind described, the combination with a pair of feed rollers, one of which is segmental, of a rotated reel receiving the envelops from said rollers, and sealing rollers receiving the envelops from said reel.

37. An envelop sealing machine comprising a flap moistener, a sealer, a magazine for the envelops, means for feeding the envelops singly from the magazine over the moistener and to the sealer, and means for effecting complete operative action of said devices in equal successive intervals of time, each such cycle of operations resulting in the delivery of an envelop from the magazine and over the moistener and the delivery of a different envelop to the sealer, said feeding means including means for receiving the envelops after action by the moistener and holding each of said envelops for a plurality of cycles of operation of the machine before delivering the same to the sealing means, to permit the gum to become softened before action by the sealer.

190

38. An envelop sealing machine comprising a flap moistener, a sealer, a magazine for the envelops, a drive shaft, and a series of coöordinated instrumentalities operated by said drive shaft for delivering an envelop from the magazine and over the moistener and for delivering a different envelop to the sealer at each revolution of said drive shaft, including a member operative to transfer the envelops successively from the moistener to the sealer by a series of successive movements each effected at one such revolution, whereby the envelops are delayed to permit the moistened gum to become softened before action of the sealer.

115

39. An envelop sealing machine comprising a flap moistener, a sealer, a magazine for the envelops, a drive shaft, and a series of coöordinated instrumentalities for delivering an envelop from the magazine and over the moistener and to the sealer at each revolution of said drive shaft, including a member constructed and arranged to receive an envelop from the moistener and to deliver a different envelop to the sealer at each such revolution, said last named member being operative to transfer the envelop from receiving to delivering position by a series of successive steps each effected at one such revolution, whereby the envelops are delayed.

125

130

to permit the moistened gum to become softened before action of the sealer.

40. An envelop sealing machine comprising a flap moistener, a sealer, a magazine for the envelop, a driving shaft and a series of coördinated instrumentalities operated by said shaft for delivering an envelop from the magazine and over the moistener and to the sealer at each revolution of said drive shaft, including a reel provided with a multiplicity of radial compartments one positioned for receiving an envelop from the moistener and another separated therefrom by several of said compartments positioned for delivering an envelop to the sealer, said reel being moved a step at each such revolution, whereby the envelops are delayed in movement from the moistener to the sealer to permit the gum to become softened before action of the sealer.

41. In a machine of the kind described, the combination with a pair of feed rollers, of an envelop transferring reel receiving the envelops with their flaps extended from said feed rollers, means to impart step-by-step rotation to said reel, a segmental sheath partly surrounding said reel so as to engage and partially close the flaps as the reel is rotated, and sealing rollers receiving the envelops from said reel.

42. The combination with a flap moistening device and a coöperating intermittently operated flap pressing device, of an intermittently rotated reel receiving the envelops from said moistening device, and sealing means receiving the envelops from said reel.

43. The combination with a flap moistening device and a coöperating intermittently operated flap pressing device, of coöperating feed rollers having intermittent feeding action, and an intermittently rotated reel receiving the envelops from said feed rollers.

44. The combination with an envelop magazine, of an intermittent envelop feeding device for discharging the envelops therefrom, one at a time, a flap moistening device, a rotated envelop transferring reel, intermittently coöperating feed rollers between said magazine and moistening device, intermittently coöperating feed rollers between said moistening device and said transferring reel, and sealing rollers receiving the envelops from said reel.

45. The combination with an envelop magazine and reciprocating envelop feeding device for discharging the envelops therefrom in timed succession, a flap moistening device, an intermittently rotated envelop transferring reel, a segmental sheath partly surrounding the same, feed rollers between said magazine and said moistening device, feed rollers between said moistening device and reel, and sealing rollers receiving the envelops from said reel.

46. The combination with an envelop

magazine and a moistening device, of a reel, means for feeding the envelops singly and in timed succession from said magazine to said moistening device and thence to said reel, means to impart step-by-step rotation to such reel, an envelop sealing means receiving the envelops from said reel, and an envelop packing mechanism receiving the envelops from said sealing rollers.

47. The combination with a flap moistening device and means for feeding envelops singly and in timed succession to and past the same, of a rotated envelop transferring reel receiving the envelops from said moistening device, sealing rollers receiving the envelops from said reel, an envelop ejector insuring delivery of the envelops from said reel to said sealing rollers, and an envelop packing mechanism receiving the envelops from said sealing rollers.

48. The combination with a flap moistening device and means for feeding envelops singly and in timed succession to and past the same, of an envelop transferring reel having a multiplicity of radial compartments, envelop sealing means positioned to receive the envelops from said reel, and means for imparting an intermittent step-by-step rotary movement to said reel to bring the compartments successively into receiving and discharging positions.

49. The combination with a flap moistening device, of an envelop transferring reel having a multiplicity of radial compartments, coöperating rollers for directing the envelops from said moistening device to an upturned compartment of said reel, sealing rollers receiving the envelops from a downturned compartment of said reel, and means to move the reel intermittently to bring the compartments by a series of timed successive steps from the upturned to downward position.

50. The combination with a flap moistening device and means for feeding envelops singly and successively to and past the same, of a rotary envelop transferring reel having a multiplicity of radial compartments arranged to receive the envelops from said moistening device, envelop sealing means receiving the envelops from said reel and an intermittently operated envelop ejector for insuring the discharge of the envelops from said reel.

51. The combination with a flap moistening device and envelop sealing means of means for feeding envelops singly and in timed succession over the moistener and to the sealer, including an envelop transferring reel having a multiplicity of radial compartments arranged to receive the envelops from said moistening device at a relatively high point and to deliver the same to said envelop sealing means at a relatively low point, and an intermittently operated

envelop ejector timed to insure downward discharge of the envelopes from the lower-most compartment of said reel to the said envelop sealing means.

5. 52. The combination with a flap moistening device, of a rotated envelop transferring reel having a multiplicity of radial compartments, coöperating rollers for directing the envelopes from said moistening device to an upturned compartment of said reel, sealing rollers receiving the envelopes from a downturned compartment of said reel, and an intermittently operated envelop ejector device for insuring delivery of the envelopes from said reel to the said sealing rollers.

53. The combination with a flap moistening device and a sealer, of a rotated envelop transferring reel receiving the envelopes with open flaps from the said moistening device and conveying them into position to be discharged by gravity to the sealer, means associated with the said reel and operating under rotation of the latter to turn the moistened flaps toward closed positions and to direct the flap against the body of the envelop as the same is discharged.

54. The combination with a flap moistening device and a sealer of a rotated envelop transferring reel receiving the envelopes with open flaps from the said moistening device and conveying them into position to be discharged by gravity to the sealer, means associated with the said reel and operating under rotation of the latter to turn the moistened flaps toward closed positions and to direct the flap against the body of the envelop as the same is discharged, and an envelop ejector arm having an action timed for insuring the discharge of the envelopes.

55. The combination with a flap moistening device and a rotated reel, of means for pulling the envelopes over said moistening device and delivering them to the reel with their moistened flaps open, a fixed segmental sheath partly surrounding said reel and en-

gaging said flaps as the envelopes are moved, and sealing means receiving the envelopes from the said reel at the lower portion of said sheath.

50

56. The combination with a flap moistening device, of a rotated reel having a multiplicity of radial compartments, means for directing the envelopes from said moistening device into an upturned compartment of said reel with their moistened flaps open, a segmental sheath partly surrounding said reel and operating under rotation of said reel to turn the moistened flaps toward closed position, and sealing rollers receiving the envelopes from the downturned compartment of said reel.

55

57. The combination with a moistening device, of a rotated envelop transferring reel having a multiplicity of compartments made up of laterally spaced pairs of prongs, means for pulling the envelopes over said moistening device and delivering them between the prongs of said spaced pairs, and sealing means receiving the envelopes from said reel.

60

58. The combination with a flap moistening device, of a rotated envelop transferring reel having compartments made up of transversely spaced pairs of prongs, means for pulling the envelopes over said moistening device and delivering them between the prongs of said spaced pairs, a segmental sheath partly surrounding said reel, sealing rollers receiving the envelopes from said reel, and an intermittently operated envelop ejector arm extended between the laterally spaced pairs of reel prongs and operative to insure delivery of the envelopes from said reel to said sealing device.

70

In testimony whereof we affix our signatures in presence of two witnesses.
